UNITED STATES PATENT OFFICE.

WILLIAM B. FOSTER, OF UTICA, NEW YORK, ASSIGNOR TO FOSTER BROTHERS MANUFACTURING COMPANY, OF UTICA, NEW YORK, A CORPORATION.

MOVABLE CUSHION FOR COUCH-HAMMOCK BACKS AND THE LIKE.

1,270,807.

Specification of Letters Patent.

Patented July 2, 1918.

Application filed November 27, 1914. Serial No. 874,141.

To all whom it may concern:

Be it known that I, WILLIAM B. FOSTER, of Utica, in the county of Oneida and State of New York, have invented certain new and useful Improvements in Movable Cushions for Couch-Hammock Backs and the like; and I do hereby declare that the following is a full, clear, and exact description thereof, which will enable others skilled in the art to which it appertains to make and use the same, reference being had to the accompanying drawings, and to the reference-numerals marked thereon, which form part of this specification.

The purpose of my present invention is to provide a movable cushion for couch hammock backs and similar articles which shall be of improved construction and adapted to add to the comfort and use of such hammocks.

A further purpose of my invention is to provide a movable cushion which in one position will extend its upholstered or cushioned surface in a forward direction from the back rod or back frame of the hammock and which may be readily shifted or swung about said back rod to a position to the rear of said back rod.

A further purpose of this invention is to provide a hingedly mounted back cushion so constructed and mounted that the occupant may at will have a well padded cushion extending some distance forward of the back rod of the hammock or by simple movement may have a relatively flat surface practically on a line with the said back rod.

A further purpose is to combine with such a swinging back cushion a flexible back or back screen or wind shield depending from the lower edge of the cushion when the cushion is in forward position and operating to cover the flat side or basis of the cushion when the cushion is turned to rearward position.

Figure 1 is a perspective view of a couch hammock to which my device has been applied with the cushion in forward position.

Fig. 2 is a perspective view of a couch hammock equipped with my device, the cushion being in rearward position.

Fig. 3 is a rear view of one end of the back rod and the movable cushion with the cushion in forward position.

Fig. 4 is a detail vertical sectional view on line 4—4 of Fig. 3.

Referring to the drawings in a more particular description my invention is illustrated as used in connection with a couch hammock having a main frame 10 supported in any suitable way as by chains 11 and 60 having a back frame or rod 12 which may preferably be composed of a rod or section of pipe extending the length of the hammock and supported above the frame work 10 of the hammock by means of its ends 13 65 being turned down and extended to the frame work of the hammock. As illustrated in the drawings the back rod is supported in movable relation to the main frame 10 by means of the lower ends of the back 70 frame being pivotally connected to the main frame 10 while an arm 15 having its lower end pivotally connected to the main frame 10 at 14 has its upper and rearward end provided with a series of notches 16 any one 75 of which is adapted to engage an outwardly extending button 17 on the end rod 13 of the back frame.

I have illustrated my invention in connection with a hammock having its back frame 80 in adjustable relation to its main frame, but it will be understood that I do not limit the application of my invention to use in connection with such a movable back frame as it will be obvious that the movable cushion 85 contemplated by my invention is as applicable to a couch hammock or the like having a rigid back frame.

To the top of the back frame of the hammock or to the back rod 12 is hingedly 90 mounted the relatively flat side or basis 18 of a cushion 19 which has its opposite surface 20 spaced the desired distance from the basis of the cushion and held in outward or crowning form in a yielding or resilient 95 manner common to cushions as by springs 21 and upholstering packing 22. The hinge or pivotal connection between the cushion basis 18 and the rod 12 may conveniently be formed by straps 23 having their ends 100 firmly secured to the cushion basis as by rivets 24 while the central part of the straps is formed with a rounding offset 25 closely fitting or straddling the round back rod 12 as is clearly shown in Figs. 2 and 3. Means 105 are provided to prevent the cushion 19 moving longitudinally of the back rod 12 which means may conveniently be short pins 26 projecting from the back rod 12 on opposite sides of one or more of the straps 23. 110

Means are provided to limit the swinging movement of the cushion at the extremes of its forward and backward movements respectively so that the flat or base side 18 of the cushion will be substantially in a line with the plane of the back frame or in a line with the end rods 13 of the back frame. As the most convenient and preferred form of such limiting means the flat side 18 of the cushion is made long enough to overlap the end rods 13 of the back frame so that said flat side will rest against the front of the end rods 13 when the cushion is in forward position and will rest against the rear side 15 of said end rods 13 when the cushion is in rearward position.

This movable cushion may also be readily combined with or used as a convenient support for a canvas or other flexible back or 20 wind shield to fill the space between the seat of the hammock and the lower edge of the movable cushion. The upper edge 27 of such flexible back or wind shield 28 is secured in any desired manner to that edge of 25 the movable cushion which is downward when the cushion is in forward position. With the cushion in this position the flexible back 28 depends from said cushion between the end rods 13 of the back frame to 30 a point considerably below the seat of the hammock. The moving of the cushion 20 from forward to rearward position operates to raise what was the lower edge of the cushion to be its upper edge and so bodily moves 35 the flexible back 28 upward to the position shown in Fig. 2 where said flexible back extends from the upper edge of the cushion down in front of the flat or base side of the cushion and in front of the back rod 12 and 40 the hinge straps 23 and then hangs downward to a point to the rear of and sufficiently below the seat to effectively close the back of the hammock.

The arrangement of the movable back 45 upon the back rod is such that the back cushion of its own weight aided by the friction of the hinge tends to remain in either forward or backward position as once adjusted, but the cushion is so balanced upon the back 50 rod that if an occupant of the hammock desires to tilt the cushion from forward position to an angle part way back it may readily be done by pressure of the shoulders or head against the cushion.

I have illustrated the couch hammock in 55 the drawings as being provided with a back rest 29 that may lie substantially flat upon the main frame as shown in Fig. 1 or that may be raised to desired position as shown 60 in Fig. 2. Furthermore this back rest may be provided with an extension head rest 30 supported in movable relation to the back rest 29 as shown in Figs. 1 and 2. Where a couch hammock is provided with such a 65 movable back or head rest my invention of

a movable back cushion is particularly advantageous as it allows a cushion for the back to project sufficiently forward to be comfortable when the person is sitting in the hammock with his back to the back of the 70 hammock and provides means for moving this cushion out of the way of the back rest or head rest when the same are to be raised to elevated position such as shown in Fig. 2. If the back cushion were not thus movable 75 either the cushion would have to be thinner or the back frame moved back when it is desired to elevate the back rest or head rest from the main frame of the hammock. My arrangement also enables me to use a back 80 rest or head rest of the full width of the main frame of the hammock.

What I claim as new and desire to secure by Letters Patent is:

1. In combination with a seat, a back rod 85 above the rear of the seat, end rods pivotally connected at their lower ends to the seat and at their upper ends holding the back rod swingingly spaced from the seat, means to hold the end rods at desired angle to the 90 seat and a body-support of considerable thickness pivotally mounted upon said back rod with one side immediately adjacent said back rod and adapted to form a body-engaging surface when turned to upright position toward the seat, the other side adapted when turned to upright position toward the seat to form a body-engaging surface extending farther toward said seat.

2. The combination with a seat of a rod 100 above one edge thereof, a body-support of considerable thickness and pivotally mounted upon said rod with one side relatively flat and unyielding and immediately adjacent said rod and adapted to form a body-engaging surface when turned to upright position toward the seat, the other side of 105 said body-support being yielding and adapted when turned to upright position toward the seat to form a yielding body-engaging 110 surface extending farther toward said seat and a sheet of flexible material depending from the body-support and forming a closure between the body-support and the seat at both positions of the body-support.

3. The combination with a seat of a rod 115 above one edge thereof, a body-support of considerable thickness and pivotally mounted upon said rod with one side relatively flat and unyielding and immediately adjacent said rod and adapted to form a body-engaging surface when turned to upright position toward the seat, the other side of 120 said body-support being yielding and adapted when turned to upright position toward the seat to form a yielding body-engaging surface extending farther toward said seat and a sheet of flexible material depending from the lower part of the body-support when the yielding side is toward the 125 130

seat and covering the flat side of the body-support and the back rod when said flat side is toward the seat, said flexible member at both positions of the body-support forming a closure between the body-support and the seat.

4. In a couch hammock or the like, the combination of a seat, a back rod above the rear edge thereof, a cushion having a relatively flat surface hingedly supported on said rod and an opposite resilient surface away from said rod, said cushion being adapted to be swung about said rod to a position in front of or back of said rod so that either surface may form the back-en-

gaging surface and a flexible back depending from the bottom of said cushion when the cushion is in forward position and covering the flat side of the said cushion and the back rod when the cushion is in rearward position, said flexible member at any position of the cushion forming a closure between the cushion and the seat. 20

In witness whereof I have affixed my signature, in the presence of two witnesses, 25 this 4th day of Nov., 1914.

WILLIAM B. FOSTER.
